MARTIN J. WALSH, JR., OF ST. LOUIS, MISSOURI.

MONEY-SORTING MACHINE.

1,109,026.

Specification of Letters Patent.

Patented Sept. 1, 1914.

Application filed January 24, 1914. Serial No. 814,134.

To all whom it may concern:

Be it known that I, MARTIN J. WALSH, Jr., citizen of the United States, residing at St. Louis, State of Missouri, have invented 5 certain new and useful Improvements in Money-Sorting Machines, of which the following is a full, clear, and exact description, reference being had to the accompanying drawings, forming a part hereof.

10 My invention has relation to improvements in money sorting machines; and it consists in the novel features of construction more fully set forth in the specification and pointed out in the claims.

15 In the drawings, Figure 1 is a top plan of the machine, with parts broken away; Fig. 2 is a side elevation thereof with parts of the frame or cabinet broken away; Fig. 3 is an end elevation looking to the right in 20 Figs. 1 and 2, the receptacle for mutilated tickets being removed, and the door of the cabinet partly broken away; Fig. 4 is a vertical cross-section on the line 4—4 of Fig. 1; Fig. 5 is a longitudinal vertical sectional detail on the line 5—5 of Fig. 1; and Fig. 25 6 is a longitudinal vertical sectional detail on the line 6—6 of Fig. 1.

The present invention is primarily directed to machines for automatically separating nickels (associated with coins of 30 higher denomination) from dimes and cents (and associated foreign matter), such a machine being eminently serviceable in sorting the moneys collected as fares by street-car 35 and railroad companies, the money thus sorted being subsequently readily counted by machines operating on coins of specific denominations.

The object here sought is to construct a 40 machine by which large quantities of coin can be handled in a short space of time, thus reducing the labor of separation and subsequent counting; one which may be power-driven; one which is compact and readily accessible to the operator or operators; one under ready control, and one possessing further and other advantages better apparent from a detailed description of the invention which is as follows:—

45 Referring to the drawings, C represents a cabinet or frame of any conventional design, and D, D', D'', a series of sliding drawers for the sorted coins, the drawers being mounted in any convenient mechanical manner known to the art. Surmounting 50 the cabinet, and extending over the major

portion thereof is a plate or table 1 on which the coins are initially deposited, said table being provided with perforations *o* distributed throughout the surface thereof, said 55 perforations being of a size to intercept nickels (five-cent pieces), quarters, half-dollars and dollars, but freely allowing to drop therethrough dimes, pennies (cents), and three-cent pieces. Mounted below the table 60 or plate 1 and traveling lengthwise of the cabinet is an endless belt-conveyer 2, the ends of the conveyer passing over rollers 3, 4, respectively, the roller 3 constituting the driving roller or member. The roller 4 is 65 supported by bearings 5 traversing the frame C, the outer reduced ends of the bearings being screw-threaded and carrying adjusting nuts *n* by which the slack of the belt may be taken up as well understood in 70 the art. At points intermediate the rollers 3, 4, the laps of the belt are guided by rollers 6, 6, the lower belt-lap being in addition supported against undue sag by the longitudinally disposed strips 7, carried by the 75 bottom flanges of the Z-brackets 8, the upper flanges of said brackets being secured to the bottoms of the upper side members *a* of the cabinet, said members *a* forming the immediate supports for the perforated plate 80 or table 1 (Fig. 4). Between the plate 1 and belt 2 are interposed the side ledges or strips 9 having faces *m* sloping toward the belt so as to guide the coins dropping through the openings *o* at the sides of the 85 plate 1, onto the belt (Fig. 4). The axis of the roller 3 is provided with an extension 10 on one end terminating in a square or polygonal shank 10' for the temporary application thereto of the socket of a crank-handle 90 H, should it be necessary at any time to impart rotation to said roller by hand in the event that the electric or other motor M is out of commission.

The table 1 is bounded by a wall W, said 100 wall extending around practically three sides of the four-sided cabinet, and serving in a measure to prevent the coins deposited on the plate or table 1 from rolling off. The belt conveyer 2 travels toward the left (Fig. 105 1) and discharges the coins resting thereon over a wall *w* forming the inner boundary of a chute 11, the latter flaring outwardly toward the side of the cabinet, said chute being provided with an inclined bottom *h* 110 sloping toward the discharge side of the chute, the slope or dip being substantially

at right angles to the general direction of travel of the conveyer-belt. The sloping bottom h is provided with a substantially horizontal extension h' projecting beyond 5 the side of the cabinet, the said extension being provided with a marginal flange or wall t having a gap or opening e for the discharge of the coins, the latter being received by any conventional make of counting 10 machine R attached to the forked bracket 12. A similar counting machine R' is attached to the forked bracket 12' at the end of the table 1 farthest from the chute 11. Formed in the extension or platform h' at a 15 point adjacent the base of the wall h are openings o' through which is free to drop dirt and foreign particles, the same descending into and being caught in any suitable receptacle or drawer 13. At one end of 20 the series of openings o' is a chute 14 projecting partly above and partly below the member h' through which are discarded coins of the penny denomination, the same being caught in the dirt drawer or receptacle 13 immediately beneath said chute. 25

Covering the chute 11 is a board or panel 15 on which rest receptacles 16, 17, for the deposit of quarters, and half-dollars respectively, the same being maintained against 30 displacement by the hooks or brackets 18, 18, hooking over the edge of the wall W . The panel 15 overhangs the end of the cabinet, the overhanging or overlapping portion being provided with an opening A for mutilated car tickets which are caught in a detachable receptacle 19, the latter being suspended by means of tongues 20 sliding on supporting angle-strips 21 (Fig. 6) on the principle of a cabinet drawer, or supported in any other suitable mechanical manner. 40

Under ordinary circumstances, motion is imparted to the conveyer from an electric motor M , mounted beneath or behind the inclined bottom h of the chute 11, and within 45 the confines of the cabinet C , the motor-shaft carrying a worm pinion 22 meshing with a worm-gear 23 on a counter-shaft 24, one end of which carries a sprocket pinion 25 from which leads a sprocket-chain 26 to 50 a terminal sprocket pinion 27 at the adjacent end of the roller 3. The current is supplied from any suitable source of electrical energy through wires w, w , a switch 28 being provided where convenient for turning on 55 or cutting off, the power. These features are shown more or less conventionally because well understood in the art. Features shown in the drawings, but not alluded to, are well known and require no description in 60 the present connection. L represents a door by which access may be had to the motor and driving gear, as quite obvious from the drawings.

For our present purpose we may assume 65 that the fares collected comprise a mixture

of pennies, dimes, nickels, quarters, and halves (three-cent pieces being no longer in circulation, and silver dollars being usually kept apart from the smaller denominational coin). 70

The operation of the machine under the circumstances would be about as follows:— A sack-full of mixed coins is deposited on the bed or plate 1 and the motor M is started. The coins are worked by hand across 75 the surface of the plate and toward the discharge gap or mouth e' formed between the block E and the adjacent end of the wall W (Fig. 1.), the nickels or five-cent pieces remaining on the plate, and as they come opposite the gap e' they are pushed into the mechanical counter R' (well understood in the art). The quarters and halves (which are in the minority) are picked out and deposited into their respective receptacles or 80 boxes 16, 17. The dimes and pennies and dirt drop through the openings o onto the traveling belt-conveyer (toward which they are directed on the sides by the ledges 9) and, as the conveyer advances, they are automatically precipitated over the wall w into the chute 11, sliding down the sloping bottom h thereof onto the extension h' where the dirt, and foreign matter drops through the openings o' into the drawer 13, the 85 coins being however intercepted. What pennies may be mixed with the dimes are picked out by hand and thrown into the chute 14 which delivers them into the drawer 13. The dimes are then pushed by hand through 90 the gap e into the counting machine R attached to the bracket 12. Any mutilated tickets are picked out both from the coins on the table 1 and in the chute 11 and thrown into the receptacle 19 through the opening 95 A . Should the motor M at any time be out of commission, rotation may be imparted to the roller 3 (and hence movement to the belt-conveyer) by the crank-handle H . The main object of the present machine is to 100 automatically separate dimes and pennies, from nickels, quarters and halves. The dimes and nickels predominating, it follows that the quarters and halves may be readily picked out of the nickels by hand, and the 105 pennies picked by hand out of the dimes. The coins of the larger denomination (25¢, 50¢) may be counted by hand, as well as the pennies, the dimes and nickels requiring mechanical counters R, R' , by reason of their 110 great bulk. A machine of the character here described has a maximum capacity, the several hundred openings o in the plate almost instantly discharging the dimes and pennies onto the belt 2 the moment the 115 charge is dumped onto the table 1. In the drawings, the nickels are represented by the reference letter G , and the dimes and pennies by G' . 120

The invention is obviously not restricted 130

in its application to coins of the specific denominations alluded to, but is to be understood as applicable to coins of any denomination or diameter, or to other material, 5 whether money or not, capable of being sorted.

Though termed a "sorting" machine, because it separates coins of different denominations from one another, it is inherently a 10 sizing machine, because separating the different sizes of disks from one another.

Having described my invention, what I claim is:—

1. In a money sorting machine, a perforated member for the deposit of the original coin operating to intercept coins of specific denominations, and allowing those of other denominations to pass through the openings thereof, a traveling member for intercepting 20 the coins discharged through said perforated member, and conducting said intercepted coin to a suitable point of discharge, a second perforated member positioned below the plane of, and beyond the first perforated member for receiving the coins discharged from said traveling member, and operating to intercept said coins and direct 25 their discharge across the general direction of movement of the traveling member and 30 allow the dirt and foreign material to pass therethrough.

2. In a money-sorting machine, a stationary depositing table for the coins, perforated to discharge coins of certain denominations and intercept coins of other denominations, a discharge for the intercepted coins leading from said table, a conveyer below the table for intercepting the coins discharged through the table perforations, 40 and for conducting the same to a suitable point of discharge, a transversely disposed chute positioned beyond the table for receiving the coins discharged from the conveyer, a perforated plate at the base of the chute 45 operating to intercept the coin delivered thereto but allowing dirt and foreign matter to pass therethrough, and means on said plate for effecting a discharge of the coin intercepted thereby.

3. In a money sorting machine, a stationary depositing table for the coins, perforated to discharge coins of certain denominations and intercept coins of other denominations, a discharge for the intercepted coins leading from said table, a belt-conveyer below the table for intercepting the coins discharged through the perforations of the table, a chute located at the discharge end of the conveyer beyond the end of the table 55 and inclined transversely to the general direction of travel of the belt, an extension leading from the inclined portion of the

chute and provided with perforations for the escape of dirt and foreign substances, and having a marginal discharge for the 65 coins, and a chute leading from said extension and extending a suitable distance above the upper surface of the same through which a portion of the coins accumulating on said extension may be discarded. 70

4. In a money sorting machine, a stationary depositing table for the coins, perforated to discharge coins of certain denominations and intercept coins of other denominations, a discharge for the intercepted 75 coins, leading from said table, an endless belt-conveyer below the table for intercepting the coins discharged through the perforations of the table, ledges disposed longitudinally of and at the sides and above the 80 belt and having faces inclining toward the belt for guiding the coins onto the belt, a chute at the discharge end of the belt beyond the table having a wall for guiding the coin thereinto and a bottom inclined transversely to the general direction of travel of the belt, a perforated extension leading from said inclined bottom and provided with a marginal discharge for the coins, a receptacle below said extension, a chute leading from the extension to the receptacle for conveying discarded coins to the receptacle, a motor in the space beneath the inclined bottom of the chute aforesaid, rollers for 85 the belt, and intermediate connections between the motor and the adjacent roller for 90 imparting movement to the belt. 95

5. In a money sorting machine, a suitable frame, a top perforated plate for the deposit of coin, an endless belt conveyer beneath the plate, means on the side of the conveyer for guiding the coins dropping through the perforations, onto the plate, terminal guide rollers for the belt, a chute beyond the perforated plate having an inclined bottom at the discharge end of the conveyer disposed transversely to the general direction of travel of the belt and receiving the discharges from the belt, a motor positioned below said inclined bottom 100 within the bounding planes of the frame, a counter-shaft actuated by the motor, a sprocket wheel on said shaft, a terminal sprocket on the roller adjacent the motor, and a sprocket chain connecting the sprockets whereby movement is imparted to the belt. 105

In testimony whereof I affix my signature, in presence of two witnesses.
